UNITED STATES PATENT OFFICE.

CHARLES MOORK AND GEORGE MOORK, OF CHICAGO, ILLINOIS, ASSIGNORS
OF ONE-THIRD TO MAX WEISS, OF SAME PLACE.

VENDING-MACHINE.

SPECIFICATION forming part of Letters Patent No. 673,884, dated May 14, 1901.

Application filed January 19, 1901. Serial No. 43,888. (No model.)

To all whom it may concern:

Be it known that we, CHARLES MOORK and GEORGE MOORK, citizens of the United States of America, and residents of Chicago, in the county of Cook and State of Illinois, have invented certain new and useful Improvements in Vending-Machines, of which the following is a specification.

The main objects of our invention are to attain simplicity and positive action in coin-controlled vending-machines; to provide improved means for discharging the packages to be vended by bringing the coin into direct contact with one of said packages; to provide an improved construction for preventing the use of iron or steel slugs as a substitute for coins; to prevent the withdrawal of a coin having a thread or string tied to same, and to provide an improved construction of chute particularly adapted for apparatus of this class. We accomplish these objects by the mechanism shown in the accompanying drawings, in which—

Figure 1 is a front elevation of a vending-machine constructed according to our invention, the front wall being partly broken away. Fig. 2 is a vertical section on the line 2 2 of Fig. 1, partly broken away and omitting the chutes for carrying packages. Fig. 3 is a rear elevation of part of the coin-carrying mechanism. Fig. 4 is a horizontal section on the line 4 4 of Fig. 2, showing the coin-carrier and omitting the casing and the parts below and at the rear of the carrier. Figs. 5 and 6 are diagrammatic views showing the operation of the carrier in bringing the coin in contact with the packages to be vended. Fig. 7 is a perspective view showing the construction of the lower part of the chutes. Figs. 8 and 9 are diagrammatic views showing the discharge of the package by one of the coins and showing said coin as afterward dropped from the carrier. Figs. 10, 11, 12, and 13 are diagrammatic views showing how the steel or iron slug is retarded by the magnet and dropped from the front of the carrier without acting upon any of the packages. Fig. 14 is a diagrammatic view showing the relative position of the thread or string and the cutters, which are intended to prevent the withdrawal of a coin attached to said thread or

string. Fig. 15 is a vertical section, partly broken away, showing the push-arm for operating the carrier and showing the lock for the drawer.

The device shown is designed for vending packages of gum and similar articles, and consists, mainly, of the casing, a series of vertical chutes which are adapted to discharge one package at a time, a coin-carrier which carries the coin against the lower package, and thereby discharges same from the chute, the magnet for preventing iron slugs from being received by the carrier in proper position to discharge a package, and the cutters for preventing the tampering with the machine by means of a coin attached to a thread or string.

The casing 1 has the removable front wall 3, having a lock 5 at its upper end. The rear wall 6 may also be made removable and similarly locked in the casing. The chutes 7 are hung in the casing at the upper part, the cross-piece 8 of said chutes being removably supported upon the blocks 9. Said chutes 75 may be readily removed after the removal of the front wall 3. Said chutes are preferably made of a series of sheet-metal troughs placed back to back and soldered together, as shown in Fig. 7. Guides 10 are secured 80 between each pair of troughs at their lower ends and are designed to cause the gum to be discharged directly toward the rear of each chute. The stops 11 are secured at the lower ends of the chutes and serve as a support for 85 the packages, which are discharged below the wall 12. (Shown in Fig. 7.) The packages 13 have a weight 14 resting upon same. Said weight is vertically movable in its chute.

The lower front wall 15 of the casing is provided with glass ports 16, through which the packages to be vended may be seen. Said wall 15 is also provided with coin-slots 17. A lower plate 18 is rigidly secured to the wall 15 for guiding the coin into the carrier 19. 90 Said plate is cut out at 20 to permit small articles to drop through in case same are substituted for the required coins. The plate 18 is provided with a series of side walls 21, as shown in Fig. 6, thus forming a series of coin-chutes. A plate 22 is pivoted above the plate 18 and serves as an additional guide for the 95 100

coins. An arm 23 is rigidly secured to the wall 15. The spring 24 is secured to the pivoted plate 22 and to the arm 23 and normally holds the plate 22 down upon the coin-chutes.

5 The plate 22 has a thread-cutter 25 secured above each coin-chute. Each of said thread-cutters has a central projection 26, which is not sharpened and is intended to bear against the coin and prevent contact of same with the cutters 25.

The wall 15 is preferably made of metal and has its sides 27 extending within the casing and furnishing a bearing for the shaft 28. The coin-carrier 19 is rigidly supported by 15 means of the arms 29 upon the shaft 28. A series of magnets 30 are secured to the front of said coin-carrier. Each of said magnets has a plate 31 secured upon the front of same, said plate having a sector 32 thereon for supporting the coins at the lower end of each coin-chute when the coin-carrier is not in proper position to receive same. The upper end of each magnet serves as a front support for a coin, and the rod 33, secured upon the 20 carrier, serves as a rear support for same. The knives 34 are secured upon the carrier and at the rear of the rod 33. Said knives project sufficiently over the back of the carrier to cut a thread, which may be secured to 25 a coin which is passed from the carrier. Said knives may be made of sheet metal, which is cut to form teeth, so as to prevent the thread from moving toward the side of the knives. A sector 35 is rigidly secured to the carrier 19 at one side. Said sector is provided with rigid teeth 36 for engaging the pawl 37, which is normally depressed by the spring 38. Said spring has its lower end curved for engaging the shoulder 39 on said pawl when the raised 30 part 40 on the sector 35 is brought in contact with the pawl. Thus when the carrier has been pushed to its rear limit the pawl will be held upwardly by the spring 38. This will permit the carrier to return to its former position 35 for receiving the coins. The lug 41 on the sector 35 will then bear against the pawl, so as to release the spring 38 from the shoulder 39. The hook 42 is rigidly secured to one of the arms which connect the carrier with the shaft. 40 50 said hook being secured below the shaft. The spring 43 is secured to said hook at its lower end and to the casing at its upper end. Said spring serves to hold the carrier normally in a position to receive the coins.

55 At the rear of the casing is a sheet-metal partition 44, which guides the packages into the lower open part 45 of the casing and guides the coins into the drawer 46. The drawer 46 has a recess 47 in one of its side 60 walls for receiving the bolt 48, which is vertically movable in the lock-casing 48. Said bolt is normally depressed by means of the spring 49 and is provided with a knob 50, whereby said bolt may be raised by the operator. The push-arm 51 projects through a slot in the front wall 15 of the casing and is provided with a lug 52, which acts against

the stop 53 on the casing. The inner end of the push-arm 51 rests upon the pin 54, which is secured to the side wall of the casing. The inner end of the push-arm 51 bears against the lug 55 on the carrier 19.

The operation of our device is as follows: When a coin is inserted in one of the coin-slots 17, the same will drop into the carrier in the position shown in Fig. 1. The operator will then push the arm 51 inwardly, and thereby carry the coin 56 into contact with the lower package 13, as shown in Fig. 6. Carrying the coin forward, the same will raise the plate 22 until the coin is free from said plate. The spring 24 will then return the plate to its former position. When the carrier arrives at its rear limit, as shown in Fig. 8, the coin 56 will have pushed the lower package 13 out of the rear part of its chute and over the partition 44. The package will now drop down behind said partition and into the lower open part of the casing. Said package may be here removed by the operator 90 from the front of the casing, as indicated in Figs. 1 and 2. When the carrier is at its rear limit, the projection 40 on the sector 35 will have raised the pawl 37, so that same will be supported in a raised position by the spring 38, 95 as before described. This will permit the carrier to freely move forward toward its rear position. As the carrier starts forward the coin 56 will be brought into contact with the rear of the package 13, which now occupies the 100 lowest position in its chute. Said coin will thus be tilted toward the rear until same is free from the partition 44, when the coin will drop down along said partition and into the drawer 46. The action of the spring 43 will 105 return the carrier in proper position to again receive the coin. In case said carrier is rearward of its proper position for receiving the coin the sector 32 will prevent any coin which may be inserted in one of the chutes from 110 leaving said chute until the carrier is again in its forward position. The lower edge of the coin will in such case bear against the sector 32. If the steel or iron slug 57 should be inserted into one of the coin-chutes, the 115 same will be held by the magnet in the position shown in Fig. 10. When the carrier is moved toward the rear by means of the push-rod 51, the slug 57 will be tilted by bearing against the plate 22, as shown in Fig. 11. 120 The coin will then drop down along the sector, as shown in Figs. 12 and 13. If a coin 58 should have a string 59 secured thereto, as shown in Fig. 14, said coin will be operated by the carrier so as to discharge one of the 125 packages. The operator will be prevented from withdrawing said coin by means of the string 59, since any effort to withdraw the coin will cut said string either on the cutters 25 or the cutters 34. The projection 26 on 130 the cutters 25 will be tapered toward the end so as to throw the string or thread upon the cutters. If the operator should permit the string to go nearly far enough so that the coin

attached thereto would discharge one of the packages, then the coin might not drop behind the carrier. In such case the string would be cut by the cutters 25. The drawer 5 46 may be removed by raising the bolt 48 after access to the device is gained through one of the removable walls. The package-chutes may be removed from the front of the casing and will be refilled by removing the 10 weights 14 and inserting the packages at the upper ends of said chutes. It will be seen that the push-arm 51 may be pulled forward independently of the carrier in case said carrier is held in an intermediate position 15 through the action of the pawl 37 upon the sector 35.

It will be understood that numerous details of the device shown may be altered without departing from the spirit of our invention. 20 We therefore do not confine ourselves to such details except as hereinafter limited in the claims.

What we claim as our invention, and desire to secure by Letters Patent, is—

25 1. In a vending-machine, the combination of a casing having a coin-slot therein; a chute in said casing for feeding packages in series; a carrier adapted to receive a coin from said coin-slot and in conjunction with said coin to cause the discharge of a package from said chute; a magnet adapted to retard an iron or steel slug and prevent its becoming seated in said carrier; and a hinged plate or arm adapted to be raised by a properly-seated coin or 35 to remove from said carrier such slug as may be retarded by said magnet.

2. In a vending-machine, the combination of a casing having a coin-slot therein; a chute in said casing for feeding packages in series 40 and having its discharge end open, with a stop for the packages at said discharge end, and a lateral opening arranged to permit the discharge of one package at a time transversely of said chute; and a coin-carrier adapted to receive a coin from said coin-slot and to carry same against the package to be removed and through the open part of the discharge end of the chute, whereby said package is discharged through said lateral opening; said 45 coin-carrier being pivotally supported to travel in an arc below the chute, and having a sector projecting under the coin-slot and adapted to retard a coin inserted in the slot while the carrier is removed from the coin- 55 slot, and to hold the coin in suitable position

to be received by the carrier upon its return toward said coin-slot, and said carrier having a magnet secured thereto and adapted to retard a steel or iron slug in its passage from the coin-slot to the carrier; and the movable 60 member projecting inwardly from said coin-slot above the path of such slug and adapted to tilt the slug upon said sector and thereby prevent its action against the packages.

3. In a vending-machine, the combination 65 of a casing having a coin-slot therein; a chute in said casing for feeding packages in series and having its discharge end open, with a stop for the packages at said discharge end, and a lateral opening arranged to permit the discharge of one package at a time transversely of said chute; a coin-carrier adapted to receive a coin from said coin-slot and to carry same against the package to be removed and through the open part of the discharge end 70 of the chute, whereby said package is discharged through said lateral opening; and a movable plate projecting inwardly from said coin-slot above the path of the coin, and adapted to guide the coin into the carrier and to be 75 raised through contact with the coin when the carrier is moved toward the chute.

4. In a vending-machine, the combination 80 of a casing having a coin-slot therein; a chute in said casing for feeding packages in series and having its discharge end open, with a stop for the packages at said discharge end, and a lateral opening arranged to permit the discharge of one package at a time transversely of said chute; a coin-carrier adapted to receive a coin from said coin-slot and to carry same against the package to be removed and through the open part of the discharge end 85 of the chute, whereby said package is discharged through said lateral opening; and a movable plate projecting inwardly from said coin-slot above the path of the coin, and adapted to guide the coin into the carrier and to be 90 raised through contact with the coin when the carrier is moved toward the chute; said plate 95 having a thread-cutter near the point of its contact with the coin.

Signed at Chicago, Illinois, this 17th day of January, 1901.
